UNITED STATES PATENT OFFICE.

BERNARD A. STERLING, OF CHICAGO, ILLINOIS.

FASTENING DEVICE.

Application filed February 10, 1923. Serial No. 27,204.

My invention relates to fastening devices, more particularly for fastening the tubes employed in waving the hair.

The object of my invention is the provision of a generally improved and simplified fastening device that may be economically produced and which may be conveniently secured in place and removed without pliers or other tools and without pulling the hair or laterally spreading the jaws of the device and without otherwise impairing the fastening ability thereof.

Another object is the provision of a device that may be conveniently released and which will firmly grip the tube and hold it in place.

The invention is illustrated in the accompanying drawing, in which—

Fig. 1 is a longitudinal section through a heating tube showing its use and the co-operation of a fastening device embodying my invention thereof;

Fig. 2 is a side elevational view of the fastening device showing in section the tube in place therein;

Fig. 3 is an elevational view of the opposite side of the fastening device with the jaws open;

Fig. 4 is an end view; and

Fig. 5 is a detail section taken on the line 5—5 of Fig. 2.

Referring to the drawing, in waving the hair it is common practice to wind a group or plurality of strands of hair 5 upon a suitable core 6 and to then wrap suitably moistened paper or other material 7 around the wound strands of hair. A suitable tube 8 of paper or the like is then placed around the wrapped strands of hair and a suitable heater is placed over the tube, all as well understood in the art.

The upper end of the tube 8 may be closed if desired, and the fastening device of my invention which is designated in its entirety at 10 is adapted for fastening the lower end of the tube 8 upon the strands of hair.

A fastening device 10 comprises a pair of relatively thin flat jaws 15 and 16 pivoted together at 17. The jaws 15 and 16 may conveniently be of metal of suitable gauge and these jaws comprise generally arcuate portions having curved ears 18 and 19, respectively, between the pivotally connected and free ends of the jaws. The ears 18 and 19 are adapted to be separated when the jaws are opened, as shown in Fig. 3, and in

closing they overlap and define an opening 20 which is contracted upon the lower end of the tube 8 as the jaws 15 and 16 are closed thereupon. The contour of the inner edges 21 of the ears 18 and 19 are preferably such that in closing the jaws upon the tube 8 a wedge-like action is imposed upon the tube to firmly grip the same in the fastening device and upon the strands of hair 5.

The free or outer end of each jaw outwardly beyond the ears 18 and 19 has a finger piece 25 which may be turned laterally into planes generally normal, the planes of the jaws 15 and 16, so that they may be conveniently grasped between the fingers for swinging the jaws 15 and 16 about their pivotal connection 17.

Pivoted at 30 upon one of the sides of the jaw 16, as, for example, upon a suitable pin 32 and between lugs 33 struck up from the jaw 16 is a detent arm 35. One end of which overlies the ear 19 on the jaw 16. The opposite end of the arm 35 extends in the opposite direction from the pivot 30 and forms a fingerpiece 36 which is adapted to be depressed to swing the opposite end of the arm 35 away from the ear 19.

The ear 18 on the jaw member 15 has a series of apertures 40 arranged in an arc about the pivot 17 as a center and the adjacent end of the arm 35 has a detent 42 which may be conveniently struck out therefrom, as shown, and which is adapted to engage in any of the apertures 40 to latch the jaws and prevent accidental opening thereof. The edge of the detent 42 adjacent the ear 18 is preferably inclined or tapered so that in closing the jaws it will spring over the ear 18 and successively into engagement with the apertures 40, and the opposite edge of the detent 42 is preferably sharper or more at right angles to the arm 35 so that the detent will remain firmly in engagement with any aperture into which it is sprung and will not be disengaged by an opening tendency of the jaws due, for example, to the tendency of the tube 8 to expand when clamped between the jaws.

A coiled spring 45 wound upon the pivot 105 pin 33 with its free ends cooperating with the fingerpiece 36 of the arm 35 and with the jaw member 16 normally urges the opposite end of the arm 35 toward the jaw member and the detent 42 into engagement with the 110 apertures 40.

The ear 18 has a marginal extension 50

which is turned back and engages over the ear 19 as the jaws are closed. This guides the ears properly into place and positively prevents any lateral spreading or separation thereof.

In use with the tube 8 in place upon the wound strands of hair, as shown in Fig. 1, for example, the jaws 15 and 16 are opened as shown in Fig. 3 and placed upon the lower end of the tube which is received between the pivoted ends of the jaws and the ears 18 and 19. The jaws 15 and 16 are then closed, crushing the wall of the tube 8 together at 58 (Fig. 1) and clamping the lower end of the tube firmly upon the strands of hair 5. When it is desired to release the tube 8 as for removal, the finger piece end 36 of the arm 35 is depressed toward the adjacent jaw 16 which swings the opposite end outwardly and the detent 42 out of engagement with the particular aperture 40 with which it was cooperating to hold the device closed upon the tube.

From the foregoing it will now be apparent that the device is simple and that it firmly grips the tube upon the hair. It is released without additional tools and without breaking the fingernails or pulling the hair and it holds the tube firmly in place.

I claim:—

1. A fastening device comprising a pair of jaw members hinged together, a pair of finger pieces at the free ends of said jaw members, cooperating ears on said jaw members between their hinged connection and said finger pieces, and a detent pivoted on one side of one of said jaw members to swing laterally with respect thereto and having means at one end for co-engagement with the ear on the other jaw member and a finger piece at its opposite end for releasing the detent.

2. A fastening device for a hair waving tube comprising a pair of relatively thin, flat jaw members hinged together, a pair of finger pieces at the free ends of said jaw members, cooperating ears on said jaw members between their hinged connection and said finger pieces, one of said ears having a series of apertures disposed in arcuate order about the hinged connection between said jaw members as a center, a detent arm pivoted on one side of the other jaw member and swingable laterally with respect thereto, a detent on said arm for engagement with said apertures, and a spring urging said detent into engagement with said apertures.

3. A fastening device comprising a pair of

jaw members hinged together, and a detent pivoted on one side of one of said jaw members to swing laterally with respect thereto and having means at one end and on one side of the pivot for said detent for co-engagement with the other jaw member to latch said jaw members against opening and a finger piece at its opposite end and on the opposite side of said detent pivot for releasing the detent.

4. A fastening device comprising a pair of jaw members, a pivotal connection between said jaw members, and a marginal extension on one of said jaw members turned back to engage over the other jaw member to guide said jaw members into proper co-relation and to prevent lateral separation thereof.

5. A fastening device for hair waving tubes comprising a pair of jaw members hinged together, a pair of finger pieces at the outer ends of said jaw members, cooperating ears on said jaw members between their hinged connection and said finger pieces, and a detent pivoted on one side of one of said jaw members to swing laterally with respect thereto and having means at one end for co-engagement with the ear on the other jaw member, and a finger piece at its opposite end for releasing the detent, said jaw members being adapted to be opened to receive a heating tube between their pivoted ends and said cooperating ears, and said ears having a wedge-like action upon closing the jaws to clamp the tube firmly therebetween.

6. A fastening device for hair waving tubes comprising a pair of jaw members hinged together, a pair of finger pieces at the outer ends of said jaw members, cooperating ears on said jaw members between their hinged connection and said finger pieces, and a detent pivoted on one side of one of said jaw members to swing laterally with respect thereto, having means for co-engagement with the ear on the other jaw member, said jaw members being adapted to be opened to receive a heating tube between their pivoted ends and said cooperating ears, and said ears having a wedge-like action upon closing the jaws to clamp the tube firmly therebetween, and a marginal extension on one of said ears turned back over the other ear to guide said ears into proper co-operation and to prevent lateral separation of said ears.

In witness wherof, I hereunto subscribe my name this 6th day of February, 1926.

BERNARD A. STERLING.
